UNITED STATES PATENT OFFICE.

RASMUS JENSEN, OF LOS ANGELES, CALIFORNIA; AGNES M. JENSEN ADMINISTRATRIX OF SAID RASMUS JENSEN, DECEASED.

CARBURETER.

1,343,455.

Specification of Letters Patent. Patented June 15, 1920.

Application filed June 20, 1916, Serial No. 104,676. Renewed September 13, 1919. Serial No. 323,648.

To all whom it may concern:

Be it known that I, RASMUS JENSEN, a citizen of the United States, residing at Los Angeles, in the county of Los Angeles and State of California, have invented a new and useful Carbureter, of which the following is a specification.

An object of this invention is the carbureting of liquid hydrocarbons.

10 Another object is to so effect the carbureting that the right proportions of liquid hydrocarbon and air will be automatically produced under varying engine speeds and under varying atmospheric temperatures.

15 Another object is to effect the foregoing by a construction of maximum simplicity and effectiveness.

The accompanying drawings illustrate the invention:

20 Fig. 1 is a plan view of a carbureter embodying the invention, one of the fastening ears being broken away for clearness of illustration.

25 Fig. 2 is an elevation of Fig. 1 looking at the thermostat side, the screw for adjusting the needle valve and the seat for said screw being shown in section for clearness of illustration.

30 Fig. 3 is an elevation mainly in section on line indicated by x^4-x^3 , Fig. 1, a portion of the throttle lever being broken away to contract the view.

Fig. 4 is a plan section on line indicated by x^4-x^4 , Fig. 3.

35 Fig. 5 is an inverted plan section on line indicated by x^5-x^5 , Fig. 3.

Fig. 6 is a fragmentary section on line indicated by x^6-x^6 , Fig. 4.

40 There is provided a substantially cylindrical or other suitably shaped float chamber 1 having at one side an offset inlet portion 2 into the upper side of which is screw-threaded a valve chamber 3 having a flanged head 4 resting against the upper end of a fuel inlet member in the form of a T 5 that is mounted on the top of the offset portion 2 and that is provided with an opening 6 adapted to be connected to a source of fuel supply. The valve chamber 3 is provided 45 with a needle valve plug 7 adapted to close on a seat 8 to control the admission of liquid fuel from the interior of the member 5 through a port 9 which opens from the interior of the member 5 to the interior of the valve chamber 3.

The lower end of the needle valve plug 7 rests upon a furcated arm 10 pivoted at 11 in the sides of the offset portion 2, the furcations of said arm 10 being in the shape of quadrants so as to straddle an annular 60 float 12 which rises and lowers in the float chamber 1 in accordance with the level of liquid hydrocarbons in said float chamber, and said furcations of the arm 10 being pivoted at 13 to lugs 14 of the float 12. Thus 65 movement up and down of the float 12 moves the needle valve 7 so as to control the level of liquid hydrocarbons in the float chamber in a manner well understood in the art.

The float chamber 12 surrounds an outer 70 air pipe 15 which projects upward from the bottom of the float chamber 12 to a level slightly above the rim of said float chamber, said air pipe in the instance shown in the drawings being integral with the float chamber 75 1, though it is understood that it need not necessarily be so. The bottom of the float chamber 1 axially thereof is provided with a circular opening 16 communicating with the interior of the air pipe 15. Into the opening 16 is inserted a tubular boss 17 projecting from the upper side of a laterally projecting air inlet member 18 having ports 19 through which to receive atmospheric air, said ports 19 being controlled by a sleeve 85 valve 20. Preferably the inlet member 18 will be connected at its outer end to a source of hot air supply, such, for instance, as a chamber, not shown, surrounding the exhaust of the engine to which the carbureter 90 is connected.

The air pipe 15 is provided in its interior from side to side thereof with a bridge piece 21, which, as shown in the drawings, may be integral with the air pipe 15, said bridge 95 piece being provided with a downwardly projecting stud 22 extending axially of the float chamber 1 and projecting through the opening 16 and projecting through an orifice 23 in the bottom of the inlet member 18, there being a nut 24 screw-threaded onto the projecting end of the stud 22 and against the bottom face of the inlet member to hold said inlet member securely in place. It is clear that the inlet member may be 100 adjusted to different positions relative to the float chamber 1 around the periphery thereof.

The bridge piece 21 is provided transversely of the axis of the float chamber 1 110

with a duct 25 having its ends opening into the float chamber 1 and communicating at the axis of the float chamber with the lower end of a nozzle 26 which is screw-threaded 5 into the upper side of the bridge piece 21.

Surrounding the nozzle 26 and in this instance integral therewith is a priming cup 27 which at its lower end joins the nozzle just above the bridge piece 21 in a curved 10 bottom portion 28, there being a port 29 from the interior of the nozzle to the space within the priming cup 27. The rim of the priming cup is on a level with the rim of the air pipe 15, and the priming cup is 15 spaced from the air pipe so as to form an annular passage communicating at its bottom with the passages 27' at the sides of the bridge piece.

Into the priming cup 27 between the walls 20 thereof and the nozzle 26 there is inserted an inner air pipe forming an air deflector 30 which projects downward from a partition 31, said partition forming the top or cover of the float chamber 1 and also forming 25 the bottom of a tubular mixing chamber 32 having legs 33 joined together at their lower ends by an annular flange 34, there being screws or equivalent 35 at the edges of said flange and partition threaded 30 into the float chamber 1 so as to tightly secure these parts together and so that access may be readily had to the interior of the float chamber by removing the screws, mixing chamber and partition.

35 It is clear that the mixing chamber 32 and float chamber 1 may be turned relative to one another to change the position of the inlet 6 circumferentially of the mixing chamber.

40 The air pipe 30 extends upward above the partition 31 and terminates in helicoidal vanes or blades 36 so as to cause any fluid discharging upward through the bore 37 of the air pipe 30 to be given a whirling motion in order to more thoroughly mix the liquid particles of hydrocarbon and air coming through said bore.

The legs 33 are spaced apart from the tubular lower end 38 of the mixing chamber 32 and extend below the level of said lower end, said tubular portion being spaced apart from the partition 31 to form an annular auxiliary air port 39 which surrounds the upper end of the air pipe 30 and 55 opens from the exterior of the mixing chamber between the legs 33 into the interior of said mixing chamber between the lower edges of the vanes 36 so that whatever air enters the port 39 will be given a 60 whirling motion the same as the mixture passing through the bore 37 and will dilute said mixture to make it less rich in hydrocarbons. The space between the legs 33 and the tubular portion 38 forms a guide for 65 an annular auxiliary air controlling valve

40 in the form of a ring adapted when in its lowermost position to close the port 39 and adapted when in its uppermost position to entirely open said port, said valve being operated to open by suction of the engine to 70 which the carburetor is attached and being operated to close by gravity. The higher the engine speed and consequently the greater the suction the greater the degree of opening of the port 39 will be as is readily 75 understood.

The valve 40 is provided in its upper edge with sockets 41 to accommodate nuts 42 screw-threaded on the upper ends of rods 43 which pass downward through the valve 80 and through the partition 31 and through the float 12 to that portion of the float chamber below the float, the lower ends of said rods being screw-threaded into a plunger 44 which together with the float chamber 85 12 forms a dash-pot to prevent sudden and irregular action of the valve, the liquid hydrocarbon in the float chamber retarding the up and down motion of the plunger.

The outlet of the nozzle 26 is controlled 90 by a needle valve 45 which is shiftably mounted in a cylindrical guide 46 formed, in this instance, integral with the vanes 36. Between the head 47 of the needle valve and a shoulder 48 near the upper end of the 95 guide 46 is a coil spring 49 tending to open the valve 45.

The valve 45 is operatively connected to the valve 40 and the connecting means are of such character as to give a definite ratio 100 of movement between the valve 40 and the valve 45 so as to secure definite proportions of air and fuel at different degrees of opening of the valve 40 and accordingly at different engine speeds. For this purpose 105 the upper end of the valve 45 is engaged by a finger 50 fixed to a rock-shaft 51 which is journaled at 52 (see Fig. 1) in the mixing chamber 32 and projects outward from the side of said mixing chamber. On the 110 outer projecting end of the shaft 51 is loosely mounted an arm 53 connected by curved thermostatic leaves 54 to a pin 55 provided with a roller 56 adapted to engage a track 57 formed by an outward turned 115 flange of an adjustable link 58 having a slot 59 to accommodate an adjusting screw 60 which is screw-threaded into the outer face of the valve plug 40, the expansive force of spring 49 operating to press the roller 56 120 against the track 57. The slot 59 and screw 60 afford means to regulate the angularity of the track 57 relative to the axis of movement of the valve 40 and said angularity of the track 57, as is clear, allows the roller 56 125 to move in a curved path around the axis of the rock-shaft 51 when the valve 40 moves up and down. The degree of opening of the needle valve 45 relative to the degree of opening of the valve 40, when the valve 130

40 is in closed position, is effected by suitable adjustable means which may be constructed as follows: The arm 53 is provided with a stud 61 extending through a socket 62 of a seat 63 which is engaged by an adjusting nut 64 screw-threaded onto the free end of the stud, said seat 63 forming the outer end of an angularly bent arm 65 that is fastened by a set-screw 66 or equivalent to the rock-shaft 51. Thus turning of the nut 64 in one direction will allow the needle valve 45 to open farther and turning of said nut in the opposite direction will cause the finger 50 to depress the needle valve against the expansive force of the spring 49 so as to more nearly close the nozzle outlet, without affecting the position of the valve 40. This gives the fuel adjustment for lower engine speeds. Adjustment of the angularity of the track 57 will change the ratio of opening of the needle valve and the valve 40, it being clear that for a richer mixture at higher engine speeds the angularity of the track will be made greater relative to the path of movement of said track and that for a less rich mixture at higher engine speeds the track will be adjusted to bring its working face more nearly into position to coincide with the path of movement of said track.

Under higher temperatures the thermostatic leaves 54 will expand to automatically reduce the degree of opening of the nozzle outlet relative to the degree of opening of the port 39, and under lower temperatures the leaves will contract to increase the degree of opening of the nozzle outlet relative to that of the port 39, thus making the mixture less rich under higher temperatures and richer under lower temperatures in accordance with engine requirements as is well understood in the art.

The valve 40 is provided with a shoudered stud 67 to journal a roller 68 which bears against one of the faces of one of the legs 33 so as to prevent rotation of said valve under the pressure transmitted through the roller 56 from the spring 49.

If desired a coil spring 69 may be placed around the stud 61 between the seat 63 and the arm 53 so as to hold the nut 64 tightly in its socket and prevent turning thereof under the influence of vibrations and shocks.

The mixing chamber 32 is provided at its outlet end with ears 70 for attachment to the mixture conducting pipe of the engine with which the device is used. The mixing chamber 32 is also provided at its discharge end with a shaft 71 having mounted thereon a butterfly throttle valve 72 for regulating the volume of mixture passing out of the carbureter so as to control the speed of the engine, the shaft 71 being provided with an arm 73 whereby turning of the shaft 71 may be effected.

In practice, assuming that the fuel inlet 6 is connected to a suitable source of fuel supply, not shown, and that the air inlet 18 is connected to a chamber surrounding the exhaust of the engine and assuming that the discharge end of the mixing chamber 32 is connected to the intake pipe of an internal combustion engine, the liquid fuel will rise in the float chamber 1, in the nozzle and also in the priming cup 27, for instance, to the level indicated at *a*, Fig. 3. When the engine is put into operation in a manner well known in the art and the throttle valve is opened but slightly, the suction of said engine will draw liquid fuel from the nozzle 26 and also from the priming cup 27 into the upper end of the air pipe 30 and thence between the vanes 36 which give the atomized fuel a whirling motion. When all of the liquid fuel in the priming cup 27 has been sucked therefrom, air entering through the inlet member 18 will be sucked upward around the priming cup and thence downward inside of said cup and thence upward through the air pipe 30 and between the vanes 36 to be given a whirling motion and intimately mixed with the liquid fuel simultaneously sucked from the nozzle 26.

If the throttle valve 72 now be opened to a greater degree, the greater suction produced by the engine in the mixing chamber 32 opens the valve 40 to admit auxiliary air through the port 39 into the intervane spaces where said auxiliary air is thoroughly mixed with the mixture passing from the upper end of the air pipe 30 to dilute said mixture. The higher the engine speed the greater will be the opening of the port 39 as is readily understood, and, as has been stated hereinbefore, when the valve 40 moves to open the port 39, the needle valve 45 is raised a proportionate degree to allow the increased suction to draw a greater volume of liquid fuel from the nozzle 26.

It is noted that the hot air passes through the air pipe 15 and, that because of said air pipe extending through the float chamber, the liquid fuel is preheated so as to enhance the gasification of said fuel when it is atomized.

It is believed that the foregoing will enable those skilled in the art to which the invention appertains to make and use the invention, it being understood that changes may be made within the scope and spirit of the appended claims.

I claim:

1. In combination, a carbureter having air and fuel valves, a track adapted to be connected to the air valve of the carbureter, a rotatively mounted shaft, a finger on the shaft adapted to govern the amount of opening of the fuel valve of the carbureter, and thermostatic leaves to turn the shaft provided with a roller to engage the track, said

- track and leaves being so disposed that movement of the track will cause the leaves to turn the shaft.
2. In combination, a carbureter having air and fuel valves, a track having a slot, means to pivot the track to the air valve of the carbureter, means to adjustably hold the track against turning on its pivot, a rotatively mounted shaft, a finger on the shaft adapted to govern the amount of opening of the fuel valve of the carbureter, and thermostatic leaves to turn the shaft provided with a roller to engage the track, said track and leaves being so disposed that movement of the track will cause the leaves to turn the shaft.
3. In combination, a carbureter having air and fuel valves, a rotatively mounted shaft, a finger on the shaft adapted to govern the amount of opening of the fuel valve of the carbureter, an arm fixed to the shaft, an arm rotative on the shaft, thermostatic leaves fastened to the rotative arm, means adapted to connect the free end of the leaves to the air valve of the carbureter, a spring between the fixed arm and the rotative arm to tend to turn the rotative arm away from the fixed arm, and means to limit the turning of the rotative arm relative to the fixed arm.
4. In combination, a carbureter having air and fuel valves, a rotatively mounted shaft, a finger on the shaft adapted to govern the amount of opening of the fuel valve of the carbureter, an arm fixed to the shaft, an arm rotative on the shaft, thermostatic leaves fastened to the rotative arm, means adapted to connect the free end of the leaves to the air valve of the carbureter, a spring between the fixed arm and the rotative arm to tend to turn the rotative arm away from the fixed arm, a stud projecting from the rotative arm through the fixed arm, and a nut screw-threaded on the stud to limit movement of the arms away from one another.
5. In combination, a carbureter having air and fuel valves, a rotatively mounted shaft, a finger on the shaft adapted to govern the amount of opening of the fuel valve of the carbureter, an arm fixed to the shaft and provided with a socket, an arm rotative on the shaft, thermostatic leaves fastened to the rotative arm, means adapted to connect the free end of the leaves to the air valve of the carbureter, a spring between the fixed arm and the rotative arm to tend to turn the rotative arm away from the fixed arm, a stud projecting from the rotative arm through the socket, and a nut screw-threaded on the stud and seated in the socket to limit movement of the arms away from one another.

Signed at Los Angeles, California, this 13th day of June, 1916.

RASMUS JENSEN.
